UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

TABULATOR PRINTING-MACHINE.

1,245,504.

Specification of Letters Patent.

Patented Nov. 6, 1917.

Application filed June 14, 1915, Serial No. 33,864. Renewed April 6, 1917. Serial No. 160,313.

To all whom it may concern:

Be it known that I, JAMES POWERS, a citizen of the United States, residing in New York, in the county of New York and State of New York, have invented certain new and useful Improvements in Tabulator Printing-Machines, of which the following is a specification.

This invention relates to improvements in tabulator printing machines coöperating with perforated record cards.

One of the main objects of the present invention is to provide an arrangement whereby a tabulating and printing mechanism can be so connected to a card analyzing mechanism that a particular group of data can with facility be tabulated and printed to the exclusion of other data contained on a card.

Another object of the invention is to provide an arrangement whereby, when desired, all the groups of data of a card can be tabulated and printed, and when only a particular group of data of such card is to be tabulated and printed, the connecting means for the other groups of data can with facility be removed so that such other groups of data will not be tabulated and printed.

Still another object of the invention is to provide an arrangement having connecting means for connecting a tabulating and printing mechanism with an analyzing mechanism any of which connecting means can be quickly removed when corresponding data is not to be recorded.

Still another object of the invention is to provide an arrangement of connecting means particularly adapted for connecting the printing and tabulating mechanism to the analyzing mechanism of the apparatus described and claimed in my copending application, Serial No. 802,363, filed November 22, 1913, which connecting means are arranged in groups to correspond with groups of data of perforated record cards, any of which groups of connecting means may with facility be removed when it is desired not to record the groups of data corresponding with the groups of connecting means removed.

These and other features, capabilities and advantages of the invention will appear from the subjoined detail description of one specific embodiment thereof illustrated in the accompanying drawings, in which—

55 Figure 1 is an end elevation of a tabulat-

ing and printing mechanism connected with an analyzing mechanism by the means forming the main subject-matter of the present invention, the card hopper being removed.

Fig. 2 is a side elevation of the same with 60 the card hopper attached.

Fig. 3 is an enlarged end elevation of the casing for the connecting means detached; and Fig. 4 is a plan view of the same.

Fig. 5 is a section along the lines 5*-5* 65 of Figs. 3 and 4.

Fig. 6 is a fragmental view in section of a corner of the casing for the connecting means.

Fig. 7 is a fragmental plan view of the pin 70 securing plates of the connecting means.

Fig. 8 is a fragmental view illustrating the manner in which the pin is secured by the pin-securing plates.

Fig. 9 is an enlarged view, partly in section, showing the pins of the analyzing mechanism and the casing of a connecting means in position with certain groups of its connecting means registering with certain groups of the pins of the analyzing 80 mechanism.

Fig. 10 is a fragmental view showing part of the means for raising the housing containing the tabulating and printing mechanism.

In the embodiment illustrated, 11 is the frame of the analyzing mechanism having at one end thereof, the left side of Fig. 2, a support 12 on which a card hopper 13 is adapted to be disposed, the hopper 13 being hinged along its outer edge to the outer edge of the support 12 so that the hopper can be swung into a position removed from the supporting members 14 and 15 and the casing 16.

In this apparatus similar to the analyzing mechanism of the apparatus illustrated in my copending application, Serial No. 802,363, the cards are fed from a hopper, in the present instance the hopper 13, to a position between the plates 17 and 18 (Fig. 9) to coöperate with the pins 19 mounted in the movable pin box 20, which pins 19, when disposed in alinement with perforations in the card being analyzed, pass through such 100 perforations and advance alined extension pins 21, after which the pin box 20 and pins 19 are retracted and the card discharged from the apparatus.

Disposed above the pin extensions 21 and 110

mounted on the frame 11, there is provided a casing 16 which in the present instance has two parallel end walls 22 and 23 narrow at their lower ends, and gradually 5 widening in their upward extent to their upper wide portions, the sides of the casing 16 being inclosed by suitable walls 24 and 25 secured to the end walls 22 and 23.

The end walls 22 and 23 are provided 10 with short extensions 26 along each of their sides forming standards for the casing 16. Two anchor pins 27 are secured to a cross-piece 28 attached to the front end wall 22, one pin 27 being disposed adjacent each 15 short extension 26 of such front end wall 22. The anchor pins 27 are provided to engage in orifices formed in the upper plate 29 of the analyzing mechanism by means of which the casing 16 is positioned on said 20 analyzing mechanism so that its pins will register with the extension pins 21.

The casing 16 is provided with a perforated plate 30 at its lower end, the perforations thereof corresponding with the perforations in the plate 29, the perforations in the plate 30 being adapted to receive the lower ends of the intermediate or connecting pins 31 of the casing 16 so that such lower ends will be in alinement and in position to coact with the extension pins 21 of the analyzing mechanism.

The pins 31 are preferably arranged in groups corresponding to groups of data on the cards to be recorded. In the present instance, there are provided securing means 35 for securing the several groups of pins 31 independent of one another, by means of which securing means the groups of pins can be removed, one group independent of 40 the other so that any number of groups of records can be taken that may be desired to the exclusion of others. The securing means comprise a plurality of bars 32 each having a plurality of notches 33 on one side 45 thereof which bars when in locking position are disposed one against the other, with the notched side adjacent to the uninterrupted side of an adjacent bar thereby forming a composite plate 34, having a plurality of 50 openings. In these resulting openings, the upper ends of the pins 31 are secured and locked. The connecting pins 31 each have a constricted portion 35 near its upper end which constricted portions are disposed in 55 the notches 33, the resulting openings formed by such notches with adjacent plates being of a size sufficient to permit the free movement of the constricted portions 35 but preventing the normal sized portions of the 60 pins 31 to pass through such resulting openings, by which arrangement, when the bars 32 are secured together, the pins 31 will be locked in position.

On the present casing, provision is made 65 for five different composite plates 34, that

is, each of the end walls 22 and 23 is provided with five different sides of securing means such as the screws 36, three screws in each set. Each set of screws 36 is provided to secure an angle iron 37, each angle 70 iron having a vertical portion provided with three notches 38, and a horizontal portion adapted to extend inwardly over the edge of an end wall and spaced from an upper edge of an end wall so as to form a groove 75 within which the ends of the bars 32 may be disposed. For securing each composite plate 34 in place, there are provided two such angle irons 37, one for each end of the plate 34, one of which is secured to the end 80 wall 22 and the other to the end wall 23. By means of the notches 38, it will be seen that by merely loosening the screws 36, the angle irons 37 may be removed.

The tabulating and printing mechanism 85 T consisting of a plurality of actuators 48 is secured in a housing 39 hingedly connected at one of its lower outer edges to the upwardly extending standards 40, the other end of the housing 39 being provided with 90 ledges 41 secured to the lower corners of the housing 39, which ledges are engaged by the standards 14 and 15 and by means of which such other end of the housing 39 is supported in position.

The standards are secured to one of the outer upper edges of the frame 11 at the discharge end of the analyzing mechanism, while the standards 14 and 15 are secured to brackets 42 of the frame 11 extending 100 outwardly from such frame at the entrance end of the analyzing mechanism between the card hopper 13 and the plates 17 and 18.

In order to permit the ready elevation of one end of the housing 39, that end which 105 is adjacent to the entrance end of the analyzing mechanism, the standard 15 serves as a jack and comprises a post 43 secured to one of the brackets 42, said post 43 having a roller 44 rotatably mounted on a pin 110 extending transversely to the axis of, and fixed in said post, and also a sleeve portion 45 having a spiral slot 46 formed in its body portion in which slot the roller 44 is adapted to travel. The sleeve 45 is provided with 115 a handle 47 extending transversely of its axis by means of which the sleeve 45 can be swung around on its axis, and due to the engagement of its slot 46 with the roller 44, the sleeve 45 will be raised when it is swung 120 around in the proper direction, which sleeve 45 having its upper end in engagement with the ledge 41 of the housing 39 will raise such housing 39 with it.

When it is desired to remove the entire 125 casing 16 or change its groups of connecting pins 31, it is only necessary to raise the housing 39 by turning the handle 47, thereupon swing the hopper 13 outward and the casing 16 can then be drawn out between the 130

standards 14 and 15 which by means of the brackets 42 are spaced far enough apart to permit the casing 16 to be passed therebetween. By this arrangement, it is contemplated that the pins will be changed when the casing 16 is removed from its position on the analyzing mechanism, but obviously the pins 31 may also be changed while the casing 16 rests on the analyzing mechanism, 10 in which latter case, however, it would be necessary to swing the housing 39 completely out of the way.

It is obvious that various changes and modifications may be made to the details of 15 construction without departing from the general spirit of the invention.

1 claim:

1. The combination with an apparatus having a tabulating and printing mechanism and an analyzing mechanism, of connecting means for connecting said tabulating and printing mechanism with said analyzing mechanism, said mechanisms being divided into corresponding groups, and said 25 connecting means also being divided into groups to connect said corresponding groups of mechanisms, said groups of connecting means being removable independent of one another so as to permit the operation of any 30 one of said groups of the tabulating and printing mechanism to the exclusion of the others.

2. The combination with an apparatus having a tabulating and printing mechanism and an analyzing mechanism, of means 35 for supporting said tabulating and printing mechanism above and at a distance from said analyzing mechanism, connecting means for connecting said tabulating and printing 40 mechanism with said analyzing mechanism and disposed between said tabulating and printing mechanism and said analyzing mechanism, and means for elevating said tabulating and printing mechanism to permit the removal of said connecting 45 means.

3. The combination with an apparatus having a tabulating and printing mechanism and an analyzing mechanism, of a housing for said tabulating and printing 50 mechanism, standards secured to one end of said analyzing mechanism and extending upwardly thereof to which one end of said housing is hingedly connected, standards at the other end of said analyzing mechanism 55 on which the other end of said housing rests, connecting means for connecting said tabulating and printing mechanism with said analyzing mechanism and disposed between said tabulating and printing mechanism and 60 said analyzing mechanism, one of said latter standards comprising a jack for elevating said tabulating and printing mechanism to permit the removal of said connecting means.

4. The combination with an apparatus

having a tabulating and printing mechanism and an analyzing mechanism, of a housing for said tabulating and printing mechanism, standards secured to one end of said analyzing mechanism and extending 70 upwardly thereof to which one end of said housing is hingedly connected, standards at the other end of said analyzing mechanism on which the other end of said housing rests, connecting means for connecting said tabulating and printing mechanism with said analyzing mechanism and disposed between said tabulating and printing mechanism and said analyzing mechanism, one of said latter standards comprising a jack for elevating 75 said tabulating and printing mechanism to permit the removal of said connecting means, said jack embracing a post, a pin extending transversely to the axis of said post and fixed thereto, a roll 80 on said pin, a sleeve adapted to fit over said post on the upper end of which sleeve said housing is adapted to rest, there being a spiral slot in said sleeve in which said roll is disposed, and a handle on said sleeve for swinging the same so that the engagement of the slot with the roll will elevate said sleeve relative to said post and thereby elevate said housing.

5. The combination with an apparatus having a tabulating and printing mechanism and an analyzing mechanism, of a housing for said tabulating and printing mechanism, standards secured to one end of said analyzing mechanism and extending 95 upwardly thereof to which one end of said housing is hingedly connected, standards at the other end of said analyzing mechanism on which the other end of said housing rests, connecting means for connecting said 100 tabulating and printing mechanism with said analyzing mechanism and disposed between said tabulating and printing mechanism and said analyzing mechanism, said latter standards being spaced apart sufficiently 105 to permit the passage of said connecting means between them when it is desired to remove such connecting means, and means connected to said latter standards for elevating said tabulating and printing 110 mechanism to permit such removal of said connecting means.

6. The combination with an apparatus having a tabulating and printing mechanism and an analyzing mechanism, of a 115 housing for said tabulating and printing mechanism, standards secured to one end of said analyzing mechanism and extending upwardly thereof to which one end of said housing is hingedly connected, standards at 120 the other end of said analyzing mechanism on which the other end of said housing rests, connecting means for connecting said tabulating and printing mechanism with said analyzing mechanism and disposed between 125 130

said tabulating and printing mechanism and said analyzing mechanism, said latter standards being spaced apart sufficiently to permit the passage of said connecting means between them when it is desired to remove such connecting means, means connected to said latter standards for elevating said tabulating and printing mechanism to permit such removal of said connecting means, and a

10 hopper hingedly connected to said analyzing mechanism adjacent to said latter standards to permit the outward swinging of said hopper when it is desired to remove said connecting means.

15 7. The combination with an apparatus having a tabulating and printing mechanism and an analyzing mechanism, of connecting means for connecting said tabulating and printing mechanism with said analyzing mechanism, a casing for containing said connecting means, said tabulating and printing mechanism having a plurality of actuators, said analyzing mechanism having a plurality of groups of pins, said connecting 20 means comprising a corresponding plurality of groups of connecting pins, means in the lower end of said casing for maintaining the lower ends of said connecting pins in alinement with the pins of said analyzing mechanism, means in the upper end of said casing for maintaining the upper ends of said connecting pins in alinement with said actuators, said alining 25 means each comprising a plurality of bars having notches on one side thereof, said bars being disposed adjacent to one another so that the side having the notches will rest against the uninterrupted side of an adjacent bar, a plurality of bars thus placed together forming a plate, the connecting pins each having a constricted portion near its upper end which is sufficiently thin to freely travel in the resulting openings formed by 30 said notched bars, such resulting openings however being too small to permit the passage of the normal sized portions of the bars so that when the connecting pins are secured between adjacent bars they will be 35 anchored in place.

40 8. The combination with an apparatus having a tabulating and printing mechanism and an analyzing mechanism, of connecting means for connecting said tabulating and printing mechanism with said analyzing mechanism, a casing for containing said connecting means, said tabulating and printing mechanism having a plurality of actuators, said analyzing mechanism having a plurality of groups of pins, said connecting 45 means comprising a corresponding plurality of groups of connecting pins, means in the lower end of said casing for maintaining the lower ends of said connecting pins in alinement with the pins of said analyzing mechanism, and a plurality of plates in the upper end of said casing, the number of plates corresponding to the number of groups of connecting pins, said plates being adapted to maintain the upper ends of said connecting pins in alinement with said actuators and to anchor said pins in said casing, the actuators being divided into groups

corresponding to the groups of connecting pins, said plates and said groups of connecting pins being removable independent of one another so as to permit the operation of any one of said groups of actuators to 70 the exclusion of others.

9. The combination with an apparatus having a tabulating and printing mechanism and an analyzing mechanism, of connecting means for connecting said tabulating and printing mechanism with said analyzing mechanism, a casing for containing said connecting means, said tabulating and printing mechanism having a plurality of actuators, said analyzing mechanism having a plurality of groups of pins, said connecting 75 means comprising a corresponding plurality of groups of connecting pins, means in the lower end of said casing for maintaining the lower ends of said connecting pins in alinement with the pins of said analyzing mechanism, and alining means in the upper end of said casing for maintaining the upper ends of said connecting pins in alinement with said actuators, said alining 80 means each comprising a plurality of bars having notches on one side thereof, said bars being disposed adjacent to one another so that the side having the notches will rest against the uninterrupted side of an adjacent bar, a plurality of bars thus placed together forming a plate, the connecting pins each having a constricted portion near its upper end which is sufficiently thin to freely travel in the resulting openings formed by 85 said notched bars, such resulting openings however being too small to permit the passage of the normal sized portions of the bars so that when the connecting pins are secured between adjacent bars they will be 90 anchored in place.

10. The combination with an apparatus having a tabulating and printing mechanism and an analyzing mechanism, of connecting means for connecting said tabulating and printing mechanism with said analyzing mechanism, a casing for containing said connecting means, said tabulating and printing mechanism having a plurality of actuators, said analyzing mechanism having a plurality of groups of pins, said connecting 110 means comprising a corresponding plurality of groups of connecting pins, means in the lower end of said casing for maintaining the lower ends of said connecting pins in alinement with the pins of said analyzing mechanism, and alining means in the upper end of said casing for maintaining the upper ends of said connecting pins in alinement with said actuators, said alining means each comprising a plurality of bars having notches on one side thereof, said bars being disposed adjacent to one another so that the side having the notches will rest against the uninterrupted side of an adjacent bar, a plu- 115

120 125 130

rality of bars thus placed together forming a plate, the connecting pins each having a constricted portion near its upper end which is sufficiently thin to freely travel in the resulting openings formed by said notched bars, such resulting openings however being too small to permit the passage of the normal sized portions of the bars so that when the connecting pins are secured between adjacent bars they will be anchored in place, said alining means and said groups of connecting pins being removable independent of one another so as to permit the operation of any one of said groups of actuators to the exclusion of others.

11. The combination with an apparatus having a tabulating and printing mechanism and an analyzing mechanism, of connecting means for connecting said tabulating and printing mechanism with said analyzing mechanism, a casing for containing said connecting means, said tabulating and printing mechanism having a plurality of actuators, said analyzing mechanism having a plurality of groups of pins, said connecting means comprising a corresponding plurality of groups of connecting pins, means in the lower end of said casing for maintaining the lower ends of said connecting pins in alinement with the pins of said analyzing mechanism, and alining means in the upper end of said casing for maintaining the upper ends of said connecting pins in alinement

with said actuators, said alining means each comprising a plurality of bars having notches on one side thereof, said bars being disposed adjacent to one another so that the side having the notches will rest against the uninterrupted side of an adjacent bar, a plurality of bars thus placed together forming a plate, the connecting pins each having a constricted portion near its upper end which is sufficiently thin to freely travel in the resulting openings formed by said notched bars, such resulting openings however being too small to permit the passage of the normal sized portions of the bars so that when the connecting pins are secured between adjacent bars they will be anchored in place, said casing having end walls, a plurality of sets of securing means secured to the upper ends of said end walls, angle irons adapted to lap over the upper edges of said end walls, a set of securing means for each angle iron, supports on the inside of the upper edges of said end walls, said alining means being adapted to be secured between said supports and said angle irons by said securing means, there being two angle irons for each plate, one at each end of a plate and each disposed on one of said end walls.
